(57) **CLAIM**

The ornamental design for a catheter tip with openings, as shown and described.

DESCRIPTION

FIG. 1 is a perspective view of a catheter tip with openings.

FIG. 2 is a front view of the catheter tip of FIG. 1.

FIG. 3 is a rear view of the catheter tip of FIG. 1.

FIG. 4 is a side view of the catheter tip of FIG. 1; and, FIG. 5 is an enlarged, fragmentary perspective view of the catheter tip showing an opening, along the area of detail in FIG. 1.

The broken lines showing portions of the catheter handle are for illustrative purposes only and form no part of the claimed design.
